KNITTING MACHINE

Wilfrid Boulaïs, Upper Darby, Pa., assignor to
H. Brinton Co., Philadelphia, Pa., a corpora-
tion of Pennsylvania

Application March 25, 1937, Serial No. 133,032

65 Claims. (Cl. 66—17)

My invention relates to knitting machines, and it is an object of the invention to produce a machine that can be varied in operation to knit in any desired sequence fabrics including such as 5 have heretofore been made on a knitting machine and also other fabrics that could heretofore be manufactured only by hand.

Another object of my invention is to provide a circular knitting machine with novel means for 10 shifting needles from one location (or needle bed) to another, whereby I may alternatively knit plain or Jersey fabric, ribbed fabric with any desired sequence of inner and outer ribs, pearl fabric, etc., in desired sequence by automatic means.

15 Another object of my invention is to provide a machine with novel means for knitting stitches twisted in either direction and for either a fractional turn or for any desired number of turns.

Another object is to provide a machine with 20 means for wrapping stitches about each other in the knitting operation.

Many other objects and advantages of my invention will appear from the description in the following specification, and from the drawings 25 which are hereby made a part of this application, and in which similar reference characters indicate similar parts.

Referring to the drawings:

25

25

General structure

In the drawings, reference character 30 indicates the main drive shaft for driving the cam rings which rotate about the needle beds. This shaft is provided with a series of gears 31, 32, 33 and 34, of which gear 31 drives a vertical shaft 35 hereinafter described. Gear 32 drives a ring gear 36 bearing pillars 37 secured to a ring 38 bearing a plate 39 on which there are supported a lower 30 needle cam set 40 and an upper sinker cam set 41. Gear 33 drives a ring gear 42 bearing pillars 43 which support a ring 44 on which the lower sinker cam set 45 is mounted. Gear 34 drives a ring gear 46 bearing pillars 47 which in turn carry a beard presser operating cam 208 (see below). The ring gears and other parts hereinafter described are carried by a fixed frame indicated in part at 50.

The upright shaft 35 drives a horizontal shaft 51 on the main frame 50 carrying gears 52, 53 for driving upper rotary parts comprising a ring gear 54 with depending shafts 55 carrying a ring 56 on which is mounted the upper needle cam set 57. Gear 53 drives a ring gear 58 carrying depending shafts 59 which bear a ring 61 on which is mounted a beard presser cam 209 (see below). The parts driven from shaft 51 are carried on a shogging frame 50a provided with annular ledges

35

35

40

or shoulders as indicated at 50b, 50c and 50d (Fig. 2), supporting the respective parts.

The stationary supports for knitting instrumentalities include a lower set comprising pillars 5 63 supporting a lower comb 64, and a ring 66 for certain pattern controlling instrumentalities including Ames trick wheels 67 (see Ames Reissue Patent No. 17,705); pillars 68 supporting a ring 69 having means for supporting in readily re-10 movable manner the radial guiding walls 70 for the needle containers and a lower series of beard pressers; and pillars 69' carrying a ring 70' on which is mounted a cylinder 71 flared outward at its upper end to provide a ring at 72 to form a lower guide for the fabric being knitted. In like manner the shogging frame 50a supports depending shafts 73 on brackets 74, said pillars bearing an upper comb 75 and a ring 76 for pattern controlling devices including Ames trick wheels 77; 15 shafts 78 carrying a ring 79 supporting an upper set of removable walls 70; and shafts 80 supporting a ring 81 which is the upper guide for the fabric passing between rings 72 and 81 to the floor or to suitable take-up means, as desired. 20 The walls 70, as best shown in Fig. 4, have their inner nose portions set into slots in cylinder rings 72 and 81 and locked in place by flat rings 70'' (Fig. 4) which are removably secured to said cylinder rings respectively. 25

30

Needle and sinker containers

For the purpose of this invention it is necessary that the needles be shiftable bodily from an operative position in one needle bank to an operative position in another bank, either selectively or as an entire series. Containers have therefore been provided for holding the needles and for shifting said containers into either of the positions indicated in Figs. 2 and 3. In each container there is a spring beard needle 82, having a shank guided by stationary studs 83 (Fig. 5) said shank being bent at 84 to prevent accidental rotation thereof.

The needle is reciprocable by means of an annular butt 85 thereon, which butt is engaged at its opposite ends by lugs on a slide 86 having a butt 87 for operation by the needle-actuating cams, said slide being movable endwise of the container (indicated generally by reference character 88) and being guided by the side walls of the container. A leaf spring 89 acts frictionally against a side of butt 87 for preventing accidental movement of the slide 86 and its needle. The needle may be rotated about the axis of its shank by means comprising a pinion 90 on a flattened portion of the shank, and a rack 91 guided in a bracket 92 at one side of the container. Lugs 93, 94 on the rack form means whereby the rack may be moved trans-60 versely of the container. A kink at 84 in the needle shank acts against the side walls of the holder to keep the beard in proper position while being pressed and loops are being formed. When such kink is opposite the windows 94' or 95' in the said side walls, the needle may be rotated.

Each container carries a sinker 95 coacting with the needle of said container whether such container is in the upper or the lower comb, for which reason the sinker has two horns, as shown in Fig. 5, to coat with the needle, it being noted that each time a container is moved from one comb to the other the needle must be rotated into proper position for knitting in the needle bank into which it is moved (see positions of needles 82, 82 in Fig. 2). The body of

the sinker comprises a narrow portion 96 bearing an operating butt 97 frictionally held in place by a leaf spring 98, and a wide portion 99 with an inclined edge to prevent that portion of the sinker from catching on the ends of the walls 5 of the container when the sinker is retracted.

At its rear end the container has an arcuate base 101 shaped for sliding engagement in the grooves of combs 64 and 75, and the front or inner ends of the containers are guided by the 10 upper and lower sets of walls 70, the gap between sets of walls being narrower than the vertical width of a container, so that a container moving out from one set will engage between walls of the other before it is free from the 15 walls of the first set. Butts 102 and 103 on bases 101 serve as means whereby the containers may be moved up or down. An arcuate bar 101' (Fig. 15) supports the front ends of the needle containers when they are in the upper comb. 20

Container operating means

For moving the containers upward there are provided an initial raising cam 104 (Fig. 2) and a main raising cam 105 (Fig. 18) carried by ring 25 44 (Fig. 2). Each container has an individual jack 106, mounted in the ring 66 directly below the container and provided with a cam butt 107 positioned to engage the lower end of the base 101 when the jack is moved horizontally 30 and radially outward. The jacks are each provided with a butt 108 for engagement with cams 109, 109' (Fig. 1) for moving the jacks respectively inward and outward, said cams being carried by a bracket 110 on the rotary ring gear 42 35 and the jacks are each provided with one or more butts 111, which may be selectively removable as in Reissue Patent No. 17,705, and the jacks are flexible so that if a butt 111 is engaged by one of a series of cam levers 112 operable by the 40 trick wheel 67 the butt 108 is moved out of reach of jack cam 109 so that the jack is not moved and the container stays down. (See Fig. 14a.)

The trick wheel 67 is carried by bracket 110 on rotary ring gear 42 and is constructed for 45 step-by-step rotation by a cam plate 113 adapted to operate a pawl and ratchet device 114, as in Reissue Patent No. 17,705, when the plate is raised. It is normally held down out of action by means of a spring 115 and is raised at desired 50 times by a cam 116 on a slidable bar 117 operable by a lever 118 pivoted at 119 and movable by means of lugs arranged according to desired pattern on a cam drum 120 on a vertical shaft 121. 55

When a jack is moved radially its butt 107 will raise the corresponding holder to carry the lug 102 to a level where it is engaged by cam 104 and subsequently a cam 105 engages under the side of the holder to lift it into proper position 60 in the upper comb, where it is held by friction and additionally by a spring-pressed detent 121'. It will be seen that any desired selection may be made among the holders in the lower comb and the desired holders will be transferred 65 to the upper comb, or all the holders may be raised by omitting a trick from a slot of the trick wheel or using a trick with all its butts removed.

For transferring the containers from the upper 70 comb to the lower one I have provided means comprising an upper trick wheel 77 carried by a bracket 122 on rotary ring gear 54, a set of cam levers 123 selectively operated by trick wheel 77 for selectively actuating jacks having operating 75

butts at 124 and having cam butts 125 for pushing the corresponding containers downward into reach of a lowering cam 127 mounted on ring 56, which cam engages the upper butt 103 and moves the container down into the proper position in the lower comb. The jacks are reciprocated by means of cams similar to those at 109 and 109' for the lower jacks, and the trick wheel is rotated step-by step by means of a cam plate 128 located on a rod 129, which is reciprocated to engage or disengage the cam from the pawl and ratchet means 130, as in Reissue Patent No. 17,705, said rod being actuated by a rock arm on a shaft 132, which shaft also carries a rock arm 131 engaging cams on a drum 133 on shaft 121, to move the cam plate 128 into and out of engagement with said pawl and ratchet means.

When a container is transferred from one comb to the other it is necessary that its needle be reversed in position (see Figs. 2 and 4) and the needle may also be rotated for making twisted stitches. For these purposes there are provided the pinions 90 and the racks 91. For moving the racks up and down to rotate the needles I have provided on a support 134 fixed to ring 44 a pair of finger cams 135 and 136, which are pivotally mounted and provided respectively with depending bent actuators 137 and 138, 137a and 138a (Figs. 3, 18, 19 and 20) mounted on levers 139, 139a and guided in brackets 139b; 139c. The actuators are operated by pattern-controlled means comprising a lever 140 on the fixed frame of the machine with a cam face at its upper end at 140a. A link 141 connects this lever to another lever 142, which is rocked by cams of different heights on drum 120 to place the actuator in idle or operative position. The cams 143 and 144 of the upper set of rack-actuating cams are operated by similar means controlled from drum 133, and including a slide 143' and a cam 144'. These cams act on the needles only when the needles are in retracted or else fully-advanced position, so as to avoid damage to the needle beards. Guard cams 135', 136', 143' and 144' serve to hold the racks in proper position and also to move a rack suitably endwise if it has been moved too far or not far enough, so as to make certain that the needle beards will be located properly with reference to the yarn to be taken.

When both cams 143 and 144 are set with their sharp ends pointing upward, as shown in full lines in Fig. 21, the loops are not twisted during a series of courses. If the sharp points are both turned downward, as in Fig. 19, the next course or row of loops, as made in the next revolution of the machine, will be twisted, but thereafter the needles do not twist their loops. Now, if both sharp points are moved upward the next course or row of loops will be twisted, but in the opposite direction from those above referred to. This takes place in one course only and thereafter the loops are not twisted. It will be obvious that if the cams are left in either the up or the down position for several courses following a course having twisted loops, the following courses will not have twisted loops.

If cam 143 is set to point upward and cam 144 to point downward the loops are twisted in course after course, cam 143 rotating the needles to twist their loops and cam 144 resetting the needles so that they can again twist their loops in the next course, so long as these cams or analogous cams remain in such position; if these positions are now reversed so that cam

143 points downward and cam 144 upward the loops are also twisted (in course after course, if desired), but in the opposite sense. In this way it is possible to reverse the twist of the loops in successive courses or in successive groups of 5 courses.

By adding rack butts, such as those shown at 93 and 94, to the opposite side of the racks 91 and by installing two additional sets of cams, such as those shown at 143 and 144, at the inner 10 side of the racks on support 134', Fig. 3, it is possible to twist some loops in a course to the right and others to the left in the same row of stitches. In such case butts may be removed from some of the racks at one side thereof and from others 15 at the other side, or some of the butts may be omitted in making the racks, but preferably the racks will have frangible butts. By suitable manipulation of the twist cams with reference to racks some of which have no butts at one of the 20 four points in question, while others have no butts at another of said points, it is possible to vary the positions of twisted stitches so as to make a great variety of ornamental variations in the fabric. 25

Needle and sinker operating cams

In Fig. 15 there are shown the sinker cams on top of bracket 160, the needle cams on bracket 158 being directly underneath said sinker cams, 30 and being shown mainly in dotted lines.

The needle cam sets 40 and 57 are similar in construction, each including a pair of cams 151 and 152 between which the needle actuator butts 81 pass, a needle advancing center cam 153 which 35 advances the needles to a yarn-taking position relatively to the yarn supplied by guide 154 to which a yarn is led by passages 154a, 154b (Figs. 13, 14 and 15), and a needle retracting cam 155 with a dwell at 156 for permitting the needles to 40 dwell while their beards are pressed, after which cam 155a retracts them farther to complete the drawing of new loops and to knit off their previously formed stitches. The needle cams of the respective sets are located on brackets 157 and 45 158 (Fig. 2), while the sinker cam sets are located respectively on brackets 159 and 160.

The sinker cams comprise an advancing cam 161, a second advancing cam 163, a coacting cam 162, and a sinker retracting cam 164. Cam 161 50 is vertically adjustable, so that it can be lowered into an inactive position in which it will not act to impart the initial advancing movement to the sinkers, which will then remain idle since their butts can be engaged by cam 163 only if first 55 advanced by cam 161. Cam 161 may be moved vertically by hand into and out of operative position and fixed in position as by means of a set-screw acting on a stem 165 fixed to cam 161, but is here shown as adjustable by means of a 60 cam 166 (Fig. 13), acting on a follower 166a on the stem 165, cam 166 being on a shaft 166b having two or more star wheels 166c operated by means of a toothed finger 166d, as in the case of the finger, etc., for actuating cam 182, here- 65 inafter described, to rotate the shaft and its cam 166.

Sinker cam 163 is adjustable in radial direction to vary the length of the stitches measured off by the sinkers 95 (Fig. 14) the notches at 166' 70 on walls 70 serving as fixed abutments across which the yarn is drawn in measuring off (see Figs. 4 and 11). For this purpose the cam 163 has a depending stem 167 that is pushed outward by a spring-pressed plunger 168. A face 75

cam 169 on a shaft 170 (Figs. 3 and 14) serves to move sinker cam 163 inward to different extents as determined by the different steps of rotation of the shaft. Star wheels in suitable number (here shown as three) 171, 172, 173 secured on shaft 170 are adapted to be actuated by a finger 174 slideable in a bracket 175, the finger being pivoted on a rockarm on a shaft 176 and having an arm 177 adapted to be moved by lugs of three different heights on a drum 178 to extents predetermined by the height of such lugs. The structure of the star wheels and their actuator is like that of the devices for operating cam 182, hereinafter described.

15 The sinker cams of the lower set 45 corresponding to cams 161 and 163 of the upper set may be similarly adjusted. In the case of the radially adjustable cam a lever 179 pivotally connected to said cam is pivoted at 180 and is urged outward by a spring 181 secured at one end to the upper arm of the lever and at the other end to a fixed frame member of the machine. A cam 182 on a shaft 183 (Figs. 25 to 27) is positioned to act on an adjustable screw 184 on the lower arm of lever 179, said cam having four faces at different distances from its axis for engagement with screw 184 to vary the inward movement of the sinkers. Shaft 183 is provided with star wheels 184a, 184b, 184c and 184d adapted to be actuated by a three-toothed finger 187 similar to fingers 174 and 166d. Finger 187 is carried by a vertically movable rod 188, which is elevated to varying extents by a four-level cam (not shown) on a rod 190 slidably mounted in the machine frame, and connected to a lever 191 pivoted at 192, the free end of said lever being positioned for engagement by lugs of four different heights on drum 120.

Each of the star wheels is here shown as having three teeth (Fig. 27) and each has a tooth missing at a different angular position about the shaft. The finger 187 also has three teeth adapted to engage those of any one of the wheels. It will be seen that whenever finger 187 is moved into position to actuate a star wheel the wheel will be turned until its blank segment comes next to the finger, regardless of whether the star wheel is so located that one, two or three of its teeth must be engaged by the teeth on the finger to 40 turn the shaft 170 and its cam 169 to the desired position. In this way the sinker-advancing cam 163 can be moved into four different positions (or more or less if preferred), and the throw of the sinkers varied to a very large extent as 45 compared with previous practice, so that short stitches can be drawn, or very long stitches, as well as stitches of intermediate length.

Beard presser and presser operating means

60 The pressers 201 of the lower set and 200 of the upper set are best shown in Figs. 4, 10 and 11 and comprise flat plates located between the guiding walls 70. The pressers 201 are guided for radial sliding movement by studs 202 carried by lower walls 70 and a flat ring 205 supported on the needle carrier separator walls 70, while the pressers 200 are similarly supported and guided by studs 206 on upper walls 70 and a ring 207 on upper needle carrier separator walls 70. Cams 208 and 209 (Figs. 4, 15 and 16) respectively actuate the two sets of pressers, they being each provided with a rear cam face at 210 acting on an edge portion of each presser of the corresponding set to retract it, and a cam face at 211 acting

on an opposed edge portion for advancing the presser for appropriate coaction with the needles.

Specific features of cam 208 are best shown in Fig. 16, and include risers 212, 213 on the rear face 210 for retracting the pressers to deflect needles of holders which are in the lower comb so that an advancing needle, for example, in the position of Fig. 10 will be raised to miss the rim of cylinder ring 81 as shown in Fig. 4, the presser having an edge face at 214 (Fig. 4) for engaging the needle shank to deflect the needle at such times. In like manner a needle whose holder is in the upper comb will be deflected downward to miss cylinder ring 72, by means of an edge face at 215 on a presser of the upper series. After 10 passing riser 212 the presser moves back to leave the needle free until the presser reaches the second riser 213 which causes the needle to be again deflected to place tension on the measured off loops of the kinked yarn, so that the yarn will be taut against the needle and will clear the ends of the beards, and then the pressers are advanced by risers 216 each presser acting to close the beard of a needle in the opposite series, i. e., a lower presser closes the beard of a needle in the upper comb and vice versa. At this time the needle is in partially retracted position due to the action of the dwell at 156 (Fig. 15). Each presser cam also has on the face adjacent the needle holder a riser 217 (Figs. 4, 16 and 17) for engagement with the sinkers of holders in the corresponding comb to maintain the sinkers in position where their horns will coat with the needles for measuring off loops, and so that the end of the sinker will not strike cylinder ring 72 (or 81) and 30 will not dig into the former loops on the needles. Adjacent to the beard pressing face of the presser at 218 there is a beveled face 219 (Figs. 10, 11, 11a) on the presser for guiding the sinker alongside the presser, and a lug 220 (Figs. 11, 11a) on 40 the presser aids in guiding the hook end of the needle. A flat piece 221 (Fig. 15) on the cam supporting plate 39 (Fig. 2) serves to prevent the sinkers from being thrown up too far by the action of lug 217 on the lower presser cam 208 45 and too great depression of sinkers in the upper comb is prevented by a similar piece directly underneath said piece 221 in Fig. 15.

Pattern mechanism

50

The features of pattern mechanism not hereinbefore described include a pattern drum cam 225 (Figs. 1, 3 and 24) for actuating a slide 226 drawn outward by a spring 226', said slide operating a 55 spring-pressed pawl 227 engaging a ratchet 228 on shield 121. A shield 229 is pivoted on shaft 121 and is connected by a link 230 to the lower end of a lever 231, Fig. 3. The upper end of this lever 231 is actuated by lugs on a chain 230'. The chain is driven by means of a drum 232 having a ratchet driven by a pawl 232' connected to slide 26. Thus the shield is so actuated as to permit the pawl 227 to engage its ratchet only when drum shaft 121 is to be rotated.

Shogging mechanism

60

The upper comb and parts secured thereto are not permanently secured to the main frame of the machine but are on a shogging frame 50a, 70 supported by an overhang at 233 resting on an annular shoulder 234 of the frame 50 whereby said shogging frame is adapted to be racked or shogged circumferentially with reference to the lower comb, and this may be done manually or by

means of such devices as those shown in Figs. 22 and 23, or by other suitable means.

At a suitable portion of the shogging frame 50a, as on a segment 250 carried by posts 13 (Fig. 23), I provide rack teeth 251, arranged for engagement by either one of a pair of pawls 252, 253. Pawl 252 is actuated by a lever 254 connected to a link 255 and so to a second lever 256, oscillated for moving the shogging frame clockwise by a cam 257 on main shaft 30. Pawl 253 is actuated for moving said frame clockwise by means including a lever 258, a link 259, a lever 260 and a cam 261 (Fig. 23), levers 256 and 260 being pivoted at 260' on a bracket 261 secured to frame 50. For determining the direction of rotation, a ring 262 is shown as superposed on the part marked 250, said ring having a horizontal slot to receive studs on a shield 264 whereby said shield is slidably supported, and the ring being held in position by means shown at 265. A depending stud 266 on the shield is engaged by a rockarm 267 on a shaft 268 which may be actuated by any suitable means for moving the shield to expose one or more teeth 251 for racking the frame 50a one or more steps in either direction. A beveled spring-pressed detent at 269 serves to center the rack segment after actuation by pawls 252, 253 to insure accurate spacing of the needles. While I have shown the racking means as applied to the upper comb, it is within the purview of my invention to rack the lower comb, if preferred.

Operation

The direction of rotation of the various needle cams, etc., is indicated by the arrow in Fig. 15. If the machine be set, for example, as in Figs. 2 and 3 with the needle holders 88 alternately in upper and lower position one-and-one ribbed fabric will be knitted. If now the order of the holders be changed to provide two up and two down throughout the series or a part thereof two-and-two ribbed fabric will be made, and other variations in the rib knitting will be obvious. During such knitting yarn will be fed to the needles between the lower ends of their beards and the outer ends of the sinkers through an eye at the inner end of part 154 (Fig. 15) and the needles, sinkers and pressers will move as indicated in Fig. 18 wherein line 235 indicates the movement of the needle butts; line 236, that of the sinker butts; and line 236', that of the presser butts, the various relative positions of the needles, sinkers and pressers being also indicated in Figs. 4, 10 and 15. As above stated the needles are lifted or deflected by contact with parts of the backwardly moving pressers to prevent collision of their heads with cylinder rings 72 and 81, and the beards are pressed by forward or inward movement of the pressers in the opposite bank when the needle butts are moving along dwell 156 (Fig. 15). The positions of the sinkers with relation to the needles for measuring off stitches are also indicated in said figure, and the extent of movement of the pressers is indicated in Fig. 4. Supposing the needles to be arranged in two-and-two relation, if it be now desired to break up the two-and-two fabric into short sections in which the ribs shall appear first on one face and then on the other, the needle holders which are up may be lowered and the lower ones may be raised by operating both of the trick wheels 67 and 71 to cause the jack butts 125 to move the container butts 103 into the path of cam 127 and to cause the jack butts 107 to raise the container butts 102 into the path of cam 104, after which

cam 105 engages under the bodies of the containers to raise the same fully into the upper comb. The needles whose heads projected below the cylinder rings 72 and 81 now have their heads above said rings and vice versa, and a length will now be knitted with the ribs that formerly appeared on a face appearing at the opposite face, in each case; i. e., the ribs are reversed. The positions of the containers may thus be reversed at any desired intervals in the knitting operation.

When the positions of the containers and their needles are thus reversed the needles of each set or bank must be rotated 180° to bring their hooks into appropriate position with reference to the yarn, as will be obvious. The transfer of the containers is performed while the needles are retracted, as indicated by the position of the cams 105, 127 in Fig. 18 with reference to the needle and sinker operation, and the rotation is done while the needles are advanced as shown by the position of cam 144. Obviously the loop must be twisted when the needle is in retracted position and the loop is in the hook of the needle. In so doing the rack moves to its opposite position (at the other end of its throw), from which it must be returned if the next loop of the wale is to be twisted. For this purpose the needle must be advanced to bring the loop upon its shank and so avoid untwisting the loop just twisted.

The twist cam being in the position indicated, it will engage the butt 93 of a rack on a container which is to be lowered from the upper comb and will rotate its needle as stated, the kink of the needle being now opposite the window 94', as in Fig. 5. In like manner the needles of the containers which are raised may be rotated by appropriately setting a twist cam in either the upper or the lower set.

It should be noted that cams 135 and 143 are really the twist cams by the action of which the stitches are twisted, the cams 136 and 144 serving only to reset the racks after a twisting operation, or to rotate needles in connection with a transfer operation, without twisting the stitches. Cams 135, 136, 143' and 144' are guard cams that hold the butts of the racks in such position that their racks will keep the needles with their beards centrally above the shanks in the lower bank, or centrally below the said shanks respectively in the upper bank. It should also be noted that while the twister cams have been shown as close together in Figs. 19 and 21 as a matter of convenience they are actually spaced to a considerable extent, as shown in Fig. 18, since the cams such as 143 act while the needles are retracted.

If it is now desired to twist one or more stitches in a course of knitting, a cam such as 135 or 143 or both may be set to rotate the needle while the stitch is in the hook, and the coating cams 136 and 144 are set to reset the rack, that being done while the needle is advanced as above explained. By twisting stitches several times between feeds, i. e., by rotating their needles by successive increments with a resetting of the rack after each such twisting rotation, it is possible to twist the stitches to a greater or less extent.

It is feasible to reverse the positions of the containers in each course if desired, it being only necessary to transfer containers, etc., as above set forth after each course of knitting or after each feed in a multiple feed machine.

Pearl knitting may be done at any desired time by positioning all needle holders in one comb for one or more courses, and then transferring them all to the other comb, and so on.

For making fabrics with long loops the sinker cams 163 are adjusted to make the loops as long as desired (within the capacity of the machine) and such loops may be twisted in like manner to 5 short loops. Or some of the long loops may be twisted while others remain untwisted in the same course.

Loops may be wrapped about one another by arranging certain needles, e. g., in the lower and 10 upper combs, causing them to draw stitches, then shogging the upper comb two needle spaces if the needles are alternated, then transferring each of the holders to the other comb, shogging the upper comb over two spaces in the same direction, and 15 transferring the holders back to the comb from which they first started thereby making a so-called cable stitch fabric. Or the needles may be placed two up, two down, two up, etc., and shogged to and fro as above described but over 20 four needle spaces. By twisting loops on themselves openings may be made in the fabric for ornamental or other purposes, the loops preferably being rather long; by wrapping a loop about another, larger openings may be made; and still 25 larger openings may be made by wrapping two or more loops about a similar number of other loops, etc. By the use of a finer yarn for the wrapped course the openings may be made still larger than would otherwise be the case.

30 Novel short loop effects may be made by twisting loops to the left in certain courses and to the right in others, with or without plain knitting in some of the wales and courses, and yarns of left twist may be combined with yarns of 35 right twist for further variations, and many other novel pattern effects may be had by the use of my machine.

During the shogging operation it is necessary that all the needles and sinkers and the yarn finger or fingers must be out of operation. In a machine of the variety herein disclosed, if the capability of shogging is desired, the needle advancing cams are mounted like the sinker advancing cams in Fig. 13, so that they may be retracted from operative position either manually or automatically, so that the needles remain in idle position, and the yarn fingers are also moved out manually or otherwise, the yarn being cut and securely held at this time, after which the shogging operation will be completed in one or sometimes in two rotations of the machine, according to the amount of shogging desired, etc.

It will be obvious to those skilled in the art that many alterations may be made in the devices herein shown and described and which constitute the form of the invention as at present preferred, all without departing from the spirit of the invention; therefore I do not limit myself to what is so shown and described except as 60 required by the state of the art.

Having thus fully described my invention, what I claim is:

1. In a knitting machine, a series of needles having loop forming means at one end only, means 65 for supporting needles of the series in either of a plurality of positions angularly related to each other, means for actuating the needles to knit when in either of said positions, and means whereby needles may be moved individually from 70 one of said positions to another.

2. In a knitting machine, a series of needles, means for supporting needles of the series in either of a plurality of positions angularly related to each other, means for actuating the needles to knit when in either of said positions, means

whereby needles may be moved laterally from one of said positions to another, and sinkers movable with said needles from one of said positions to another.

3. In a knitting machine, a series of needle holders, needles in said holders and movable relatively thereto, means for supporting said holders in either of a plurality of angularly related positions, and means whereby any individual holder may be transferred from one of said positions to 10 another.

4. In a knitting machine, a series of needles, holders for the individual needles, means for supporting said holders in either of a plurality of angularly related positions, means whereby a 15 holder may be transferred from one of said positions to another, and sinkers in said holders and movable therewith.

5. In a knitting machine, a series of needles, holders for said needles, means for supporting the holders in either of a plurality of angularly related positions, means whereby the needle holders may be transferred from one of said positions to another, and separate needle actuating means for operating needles in either of said positions.

6. A device as in claim 5, including sinkers in said holders.

7. In a knitting machine, a series of needles, means for supporting said needles in either of a plurality of angularly related positions, means whereby any one needle individually or all of the needles may be given an oscillatory movement from one of said positions to another, and means for actuating needles in each of said positions.

8. In a knitting machine, a circular series of independent needles, means for supporting each of said needles in either of a plurality of angularly related knitting positions, a set of needle reciprocating cams for actuating the needles to knit in one of such positions, an independent set 40 of needle reciprocating cams for actuating needles in another of said positions and means for transferring all the needles of the series from one such position to another by oscillatory movement of the needles.

9. In a knitting machine, a series of needle holders, needles each individual to a holder, means for reciprocating the needles with reference to their holders, means for supporting said holders in either of a plurality of angularly related operative positions, and means whereby a holder may be transferred from one of said positions to another by oscillatory movement of the holder. 50

10. A device as in claim 9, including means for selectively predetermining the transfer of the 55 holders.

11. In a knitting machine, a series of spring beard needles, a holder for each needle, means for supporting the holders in either of a plurality of positions, means for actuating the needles to knit in either of said positions, and sinkers and beard pressers coacting with said needles in either of said positions.

12. A device as in claim 11, there being for each needle position a beard presser individual to that 60 position.

13. A device as in claim 11, there being in each holder a sinker operatively related to the needle in either of its positions.

14. A device as in claim 11, including means for 70 transferring holders selectively from one position to another by an oscillatory movement thereof, and means for rotating on their axes the needles of the holders so transferred.

15. In an independent needle knitting machine,

- 8 a series of needles, means for reciprocating said needles to cause them to knit, and means for rotating needles of the series on their axes between movements of reciprocation.
- 5 16. In a knitting machine, a series of needles having shanks with butts thereon, means acting on said butts to reciprocate said needles independently, and means for rotating needles between movements of reciprocation.
- 10 17. A device as in claim 15, including means to rotate such needles when in position to twist their loops, and means for rotating them when in sufficiently projected position to insure against twisting their loops.
- 15 18. A device as in claim 16, including means for rotating such needles when in position to twist their loops, and means to rotate them when sufficiently projected to be incapable of twisting their loops, said rotating means being arranged so as to be capable of rotating said needles in either direction about their axes in each of said positions.
19. In a knitting machine, independent needles, means for reciprocating said needles in a knitting operation, and means for rotating them at will in either direction about their axes when they are in a position to twist their loops.
20. In a knitting machine, a needle holder comprising a flat casing having side walls with apertures therein, a rotatable spring beard needle and a sinker between said walls and each projecting from an end of the holder, the shank of such needle having a lateral extension and said walls being apertured to permit said extension to rotate only at certain predetermined positions of the needle, and means on the holder for rotating the needle when in such position.
21. In a knitting machine, a needle holder having spaced-apart side walls, a rotatable spring beard needle in the space between said walls, and means on the holder for rotating the needle on its axis, said needle and said walls providing coacting means whereby such rotation is prevented except in certain predetermined positions of the needle.
22. In a knitting machine, a needle holder having spaced-apart side walls, a rotatable needle between said walls, and means on the holder for rotating the needle, said walls and said needle being provided with means for preventing rotation of the needle except at a predetermined position of the needle relatively to the holder.
23. In a knitting machine, a needle holder, a needle mounted in the holder for reciprocation and rotation relative to the holder, and means for preventing rotation of the needle except at particular longitudinal positions thereof in the holder.
24. In a circular knitting machine, a series of spring beard needles, holders individual to each needle, means for supporting said holders in either of two angularly related positions, a pair of rings located adjacent the verge of the forming fabric, the hook of an advanced needle in one of said positions of a holder passing said rings at one side thereof while the hook of an advanced needle in the other position of the holder passes to the other side of said rings, and the fabric passing between said rings.
25. A device as in claim 24, including a sinker in each holder, and means for moving the sinkers each into operative relation to its needle in each of said positions of the holder.
26. A device as in claim 24, including means for transferring said holders selectively from one of
- 7 said positions to the other, and means for rotating the needle of each transferred holder approximately 180° on its axis.
27. A device as in claim 24, including individual beard pressers for the needles in each of said positions, and means for moving said pressers to deflect the needles away from said rings as they are being moved endwise.
28. A circular independent needle knitting machine having a series of needles, means whereby said needles may be supported in either of a plurality of angularly related positions which positions intersect adjacent the hook ends of the needles, and means whereby the needles may be transferred individually or collectively from one of said positions to another.
29. A device as in claim 28, including selectively controlled means for rotating said needles on their axes.
30. A device as in claim 28, said needles having spring beards, and said device including means for rotating a transferred needle on its axis.
31. A device as in claim 28, said needles having spring beards, and said device including means for rotating a transfer needle on its axis, double-acting sinkers transferable with the needles, and operating means for the sinkers comprising means for positioning the sinkers operatively with respect to the needles in each of the needle positions.
32. A circular independent needle knitting machine having a series of needles, means whereby said needles may be supported in either of a plurality of angularly related positions which positions intersect adjacent the hook ends of the needles, and means whereby the needles may be transferred individually from one of said positions to another, sinkers transferable with the needles, and sinker-actuating means adjacent each needle position including means for varying the throw of the sinkers.
33. A knitting machine as in claim 32, including means for rotating individual needles on their axes to bring their hooks into either of two opposite positions, said sinkers being arranged to coact with said needles in either of said positions.
34. A device as in claim 32, said needle-transferring means and said sinker-throw-varying means being each pattern controlled.
35. A device as in claim 32, said sinker actuating means including a sinker advancing cam, a rotatable shaft, and a cam on said shaft for adjusting the sinker advancing cam.
36. In a knitting machine, a series of independent spring beard needles, means for reciprocating said needles, means for rotating needles individually through an arc of 180°, sinkers each arranged in substantial parallelism to the shanks of an adjacent needle and shaped to sink a yarn to the hooks of adjacent needles in either of the positions of rotary adjustment of the needles, and means for moving the sinkers in substantial parallelism to the movement of such adjacent needle.
37. A circular independent needle knitting machine having a series of needle holders arranged circumferentially of the machine, a needle and a sinker in each of said holders, upper and lower sets of sinker and needle actuating means, and means whereby the individual holders may be moved to bring their needles and sinkers into operative relation with either one of said sets.
38. A device as in claim 37, including pattern controlled means for transferring said holders either individually or collectively.
39. In a circular knitting machine, upper and

lower circumferentially extending combs, needle holders each engaged with a comb and transferable from one comb to the other, needles in said holders with their hooks projecting at a part of the holder remote from the comb-engaging portion, and yarn-feeding means arranged to feed a yarn to said needles in either position of the holders.

40. A device as in claim 39, including means for shogging one of said combs relatively to the other.

41. In a knitting machine, a pair of spaced-apart combs, each provided with arcuate grooves, individual grooves in each comb being adapted to register with grooves in the other comb, needle holders having bases fitting in said grooves and adapted to be moved from one comb to the other, reciprocating needles in said holders, yarn feeding means arranged to feed a yarn to the needles in either position of the holders, and needle cams operatively related to each holder for operating the needle therein to cause them to knit said yarn.

42. In a knitting machine, a pair of co-axial circular combs, a series of independent needle holders transferable from comb to comb, knitting needles carried by the holders, the needles in one comb adapted to extend crosswise of needles in the other holder, means for operating the needles in either of said positions to cause them to coact in knitting a fabric, and means for shogging one of said combs circumferentially of the machine relatively to the other comb.

43. In a circular knitting machine, means for supporting knitting needles in either of a plurality of angularly related positions, a series of needles transferable selectively from one of said positions to another, means for operating needles to knit when in either of said positions, and means for shogging needles that are in one of said positions laterally with reference to needles in another of said positions.

44. In a knitting machine, a series of needles, means for supplying a yarn to said needles, means for actuating said needles to knit a fabric from said yarn, and means for moving selected groups of said needles so as to wrap their loops about one another.

45. In a knitting machine, a series of needles, means for supplying a yarn to said needles, means for supporting needles of the series in either of a plurality of angularly related knitting positions, means for actuating said needles to knit said yarn in either of such positions, means whereby needles may be transferred individually from one of such positions to another, and means for shifting needles laterally of the series, whereby loops drawn by the needles may be wrapped about one another.

46. In a knitting machine, a series of individual needle holders, means for supporting said holders in either of a plurality of knitting positions, each of said holders carrying a knitting needle, a sinker and needle rotating means, means for actuating the instrumentalities carried by the holder in either of the knitting positions of the holder; and means whereby said holders may be shifted laterally with reference to said supporting means.

47. In a knitting machine, a series of spring beard needles, yarn-measuring sinkers coacting with said needles, and cams for actuating said needles and sinkers including a sinker advancing cam movable into and out of position for initial advancing the sinkers, and a main sinker advancing cam to move farther sinkers partially advanced by the first-named sinker cam.

48. A device as in claim 47, including means for moving the second-named sinker actuating cam for varying the throw of the sinkers.

49. A device as in claim 44, including yarn-measuring sinkers coacting with said needles, sinker cams including an advancing cam therefor, and pattern controlled means for positioning said cam so as to lengthen the stitches to be wrapped about each other.

50. In a knitting machine, a series of reciprocating independent needles, supporting means including fixed walls between said needles, sinkers movable substantially in parallelism with adjacent needles, and fixed abutments on said walls over which yarn is measured off by said sinkers in feeding said needles.

51. In a knitting machine, a series of needles, individual holders therefor, means for supporting said holders in either of a plurality of knitting positions including fixed walls between said holders, sinkers in said holders movable approximately parallel to adjacent needles, means for reciprocating said needles and sinkers in either position of the holders, means for reversing the needles when their holders are transferred from one such position to another, and abutments on said walls about which a yarn is measured off by the sinkers in feeding said needles.

52. A device as in claim 51, each sinker being constructed and arranged to coact with adjacent needles in either position of the needles.

53. A method of knitting on independent needles of a circular knitting machine arranged in separate circular series with their hook ends extending in the same general direction, comprising drawing long loops on a plurality of neighboring needles in each series, shogging those of such plurality of needles that are in one of said series laterally with respect to the others, then shifting each of such plurality of needles into the other of said series, then shogging those of said needles which are in one of said series in the opposite direction to the previous shogging motion, and then removing them to their original positions in the respective series.

54. In a knitting machine, a series of needles, means for supporting said needles in either of a plurality of angularly related positions, means for imparting a rocking movement to a needle for transferring it from one such position to another, and independent sets of needle reciprocating means for actuating needles to knit when in either of such positions.

55. A knitting machine as in claim 54, including sinkers individual to the needles and each sinker rocking with its needle in a needle transferring operation.

56. A device as in claim 54, including pattern-controlled means for transferring needles selectively from one of said positions to another.

57. In a knitting machine, a series of spring needles, means for supporting the needles of the series in either of a plurality of angularly related positions, means for rocking a needle from one of said positions to another, beard pressing means operative on the needle in one of said positions, independent beard pressing means operative on the needle in the other of said positions, and means for causing the needle to knit when in either of said positions.

58. A method of knitting ornamental fabrics comprising arranging needles in two spaced-apart sets with their hook ends arranged to take the same yarn, drawing loops on a pair of adjacent needles each of which is in a different one of

said sets shogging the needle of one set laterally past the other of said needles, shifting each of said needles into the other set, shogging said needles back again, shifting each needle back to its original set, and thereafter knitting off the loops of said needles.

59. A method as in claim 57, including the step of twisting one or more of the loops before knitting them off.

10 60. A method of making ornamental knitted fabrics comprising drawing stitches on a plurality of needles in a course, rotating one or more of said needles in one direction and one or more others in the opposite direction to twist their 15 respective loops in opposite directions, and subsequently knitting off to form oppositely twisted stitches.

61. In a knitting machine, a series of needles, means for supplying a yarn to said needles, means 20 coacting with said needles for knitting a fabric with said yarn, and needle supporting means arranged to permit selected needles to be manipulated so as to wrap their loops about one another.

62. In a knitting machine a needle bed, a needle holder movably mounted in said bed, a needle 25 and a sinker mounted for reciprocation in said holder, and means on the holder serving to hold

the needle and the sinker respectively in their advanced or retracted positions.

63. A needle holder as in claim 62, there being a needle operating butt projecting at one side of the holder and a sinker operating butt projecting at another side of the holder, and independent friction means on the holder for maintaining the needle and sinker in their advanced or retracted positions. 5

64. In a knitting machine, a pair of slotted 10 combs arranged in parallelism, said combs each having slots in line with the slots of the other comb, a series of needles, needle holders therefor having bases shaped to fit in said slots, needle actuating means operatively related to said combs, 15 and a yarn feed positioned to supply a yarn to the needles of the series irrespective of the location of said holders in said combs.

65. In a knitting machine, independent needles, means for reciprocating said needles in a knitting 20 operation, and means arranged to rotate needles in retracted position either in the same direction so as to twist their loops in the same sense, or in opposite directions to form oppositely twisted loops. 25

WILFRID BOULAIS.
